UNITED STATES PATENT OFFICE.

HORATIO N. LAND AND HOWARD CAMPBELL, OF RICHMOND, INDIANA,
ASSIGNORS TO GAAR, SCOTT & CO., OF SAME PLACE.

TRACTION-ENGINE.

SPECIFICATION forming part of Letters Patent No. 254,223, dated February 28, 1882.

Application filed November 25, 1881. (No model.)

To all whom it may concern:

Be it known that we, HORATIO N. LAND and HOWARD CAMPBELL, citizens of the United States, residing at Richmond, in the county of Wayne and State of Indiana, have invented 5 new and useful Improvements in Portable Engines, of which the following is a specification.

Our invention consists in certain improvements, which will be fully set forth hereinafter, 10 whereby the organization and operation of such engines are much improved.

In the accompanying drawings, Figure 1 is an elevation of the cylinder side of the machine; Fig. 2, a plan view; Fig. 3, an elevation taken from the side opposite that shown in Fig. 1. Fig. 4 is a detail view of part of the gearing, and Fig. 5 is a detail view of a portion of the under side of the engine, as will hereinafter be fully explained.

20 The boiler A is mounted upon main wheels B, turning loosely on axles C D. The front axle, C, is swiveled on a bar, C', which is secured to and depends from the boiler near its forward end. The rear axle, D, is bowed down 25 or U-shaped in the middle, d, so as to receive and support the curved fire-box A', which fits in the bow, as seen in Figs. 1 and 5. This construction brings the boiler and fire-box sufficiently low for convenience of the operators 30 and greatly improves the engine, rendering it more compact and efficient, and the axle also serves to brace and strengthen the fire-box.

Each rear main wheel, B, carries an internally-gearred ring, E and E'. The ring E on the cylinder side of the engine gears with a pinion, e, keyed to the shaft e'. This shaft turns in bearings e², mounted on the forward end of the fire-box A', close up under the boiler proper, A, as best shown in Fig. 5. The ring 35 E' on the opposite side of the engine gears with a pinion, F, which turns loosely on the shaft e', and is formed in one piece with or firmly secured to a bevel-wheel, G. Another 40 bevel-wheel, G', (see Fig. 2,) is mounted on the shaft e', so as to turn with it, close to the fire-box A', and between these two bevel-wheels G G' a gear-wheel, H, is mounted loosely on the same shaft. This wheel H is shown detached in Fig. 4, from which it will be perceived it carries two small bevel-pinions, h h,

mounted loosely on pins h' at right angles to the axis of the wheel, and having their bearings between the rim of the wheel and the cross-pieces or chords h² h². These bevel-pinions h h gear on one side with the bevel-wheel 55 G', fast on the shaft e', and on the other side with the wheel G, loose on the shaft, but rigidly connected with the pinion F, which gears directly with the internally-gearred ring E'.

The wheel H gears with the wheel I, mounted 60 on a short stud-axle, i, projecting from the side of the boiler, and the wheel I in turn gears with a pinion, J, which slides on a feather on the driving-shaft J' of the engine. This shaft J is mounted in bearings on the upper side of 65 the boiler, and is driven by the pitman J², connected to the crank-wheel J³.

The arrangement and organization of the boiler and steam-cylinder may be in any approved manner and construction.

70 The band-wheel K, from which the power of the engine is applied, is mounted upon the driving-shaft J'. By sliding the pinion J toward the main wheel the driving-shaft can be thrown out of gear with the driving-gearing, and the 75 engine will remain stationary while working. A suitable lever for shifting the sliding pinion may be employed.

From the foregoing description of the organization and gearing of our improved engine it will be seen that the power is applied 80 to the carrying-wheels in the most efficient manner, and that the machine can be caused to travel, turned, and backed with facility.

It will be understood that when the engine is moving straight forward or back the wheel H and its small pinions will drive both main wheels in the same direction, and when the machine is turning the small pinions will 85 rotate on their bearing-pins and permit the 90 unequal movement of the main wheels. The valve-rod L moves in a guide, L', at its outer end. Between this guide and the valve-chest a square stud or pin, l, is pivoted in the valve-rod, which stud fits and slides in a slot, m, in 95 a vertically-movable and rocking block or link, M. This block M is connected by a link, n, with the crank-arm N of a rock-shaft, N', which rocks in bearings n' on the top of the boiler, and is controlled by a crank-arm, O, and rod 100

P, which are moved back and forth by a lever, Q, which rocks in a guide, O', and is provided with a spring-catch, q, which engages in notches on the guide. The slotted block M is thus held 5 in any desired position.

Two pitmen or rods, R R, which are reciprocated by their eccentrics R' R' on the driving-shaft, are connected with the slotted block M at different points, one near its upper and 10 the other near its lower end.

It will be understood from this description that the slotted block is rocked back and forth by the reciprocating pitmen, and that the bearing of the square pivoted lug on the valve-rod 15 is always the center of motion. The movement vertically of the slotted block by its controlling-lever changes the position of the square lug in the slot. At one extreme of movement of the block the stud is at or near the top of the 20 slot and at the other extreme at the bottom. The reciprocation of the valve-rod is thus regulated and controlled by the position of the square lug in the rocking slotted block, for it will be understood that when the square lug 25 is at one end of the slot the motion of the valve-rod will be the reverse relatively to the ports of the cylinder of what it will be when the lug is at the opposite end of the slot, and that there will be intermediate points between 30 these extremes by which the engine can be controlled and driven at any desired speed.

On the side of the boiler, just under the cylinder, is placed a tubular receptacle, S, for tools.

A removable platform, T, for the engineer 35 or fireman is swung from the rear of the engine. The platform is sustained by two vertical hooks or pins, t, which enter apertures near its inner edge, and by two link-rods, U, which extend from the outer edge of the platform to 40 eyes u on the rear of the boiler. This stand is readily removable, and may be used or not, as desired.

By the improved organization above described we produce a portable engine which can be driven from place to place for use for 45 various purposes, and one which can be handled with facility and which is very efficient.

Having described our invention, what we claim is—

1. The combination, in a road or traction engine, of the fire-box having curved sides and bottom extending below the boiler, the continuous rear axle provided with a central bow or inverted arch adapted to support and strengthen the fire-box, driving-wheels having internally-toothed gear-rings, the shaft journaled in bearings on the front of the fire-box, and having gears meshing with said internally-threaded toothed rings, and means for actuating said shaft, substantially as shown and described. 60

2. The combination, in a road or traction engine, of an arched axle surrounding the fire-box, a shaft carrying at each end a gear-wheel supported on the forward end of the fire-box, the rear driving-wheels having internally-toothed gear-rings, the bevel-wheel G, attached to and turning loosely with the gear F, bevel-wheel G', mounted firmly on the shaft e', gear-wheel H, mounted loosely on the same shaft between the wheels G G', and provided with 65 pinions h h, adapted to gear with said wheels and the driving-shaft J', and connecting mechanism, substantially as shown and described. 70

In testimony whereof we have hereunto set our hands in the presence of two subscribing 75 witnesses.

HORATIO N. LAND.
HOWARD CAMPBELL.
